(No Model.)

J. Q. ADAMS.

PUMP HEAD.

No. 357,750.

Patented Feb. 15, 1887.

UNITED STATES PATENT OFFICE.

JOHN Q. ADAMS, OF MARSEILLES, ILLINOIS.

PUMP-HEAD.

SPECIFICATION forming part of Letters Patent No. 357,750, dated February 15, 1887.

Application filed April 19, 1886. Serial No. 199,419. (No model.)

To all whom it may concern:

Be it known that I, JOHN Q. ADAMS, a citizen of the United States, residing at Marseilles, in the county of La Salle and State of Illinois, have invented a certain new and useful Improvement in Pump-Heads, which is fully set forth in the following specification, reference being had to the accompanying drawings, in which—

10 Figure 1 represents a side elevation of a pump-head embodying my invention; Fig. 2, a front elevation of the same; Fig. 3, a vertical section of the same taken on the line *xx*, Fig. 1; Fig. 4, a plan section of the same taken on the line *yy*, Fig. 3; Fig. 5, a similar section taken on the line *zz*, Fig. 3; and Fig. 6, a similar section taken on the line *vv*, Fig. 3.

Figs. 1 and 2 of the drawings are on one scale, and Figs. 3 and 4 on the same scale, but 20 enlarged, and Figs. 5 and 6 on the same scale, but still further enlarged.

My invention relates to pumps which are designed to be operated either by hand or by a windmill, or other power adapted to give 25 the necessary vertical reciprocation to the piston-rod.

The invention relates especially to the mode of mounting the pump-handle upon the head and the devices by which it is connected to the 30 piston-rod whenever it is desired to work the pump by hand.

I will proceed to describe in detail one way in which I have practically carried out my invention, and will then point out definitely in 35 the claims the particular improvements which I believe to be new and wish to protect by Letters Patent.

In the drawings, A represents a pump-head, which may be of any ordinary construction. 40 It is surmounted by a close-fitting cap, B, which is provided with an opening, *b*, of any angular or irregular shape to correspond with the shape of the piston-rod C, which passes down through this opening in the cap. The cap is 45 fastened to the pump-head by any suitable means, set-screws *b'* being shown in the drawings for this purpose. A standard, D, rises from the cap at one side, being preferably cast in one piece therewith, which at its upper end is 50 bent or turned inward and is provided with an opening, *d*, corresponding to the opening

in the cap below, and consequently conforming to the shape of the piston-rod, which passes up through this arm of the standard. The standard is slotted centrally nearly from top 55 to bottom, and each side branch has a lug or ear, *d'*, projecting outward from the standard, these lugs being joined at their ends by a cross-bar, *d''*, thereby forming a kind of loop at the side of the standard, but preferably in one 60 piece with the latter. A link, E, is arranged within this loop and is pivoted at its lower end to the standard by any suitable device. In the drawings a pivot-pin, *e*, is shown, passing through the sides of the standard and the link. 65 The other end of the link is pivoted to the handle F by any ordinary means, and the link itself is secured to the standard in a fixed position by a pin, G, which passes through holes *g* in the upper portion of the side lugs and a 70 hole, *e'*, toward the upper or outer end of the link. These upper holes in the side lugs of the standard are made some distance inside of the cross-bar of the loop, to permit the link to swing backward and outward when the pin G 75 is removed, as and for the purpose hereinafter described.

The piston-rod C is provided with a box, H, below the upper end of the standard. If the piston-rod were large enough, this box could be 80 provided by slotting the rod; but as the ordinary piston-rod is not large enough for this purpose I construct a box from side pieces, *h*, bent angularly, as shown in Fig. 1 of the drawings, which are fastened at their respective 85 ends to sections of the piston-rod, the latter being severed at this point for the purpose. The box therefore constitutes a part of the piston-rod; but as its sides are extended outward by means of the angular bends, as shown 90 in Fig. 1 of the drawings, it is obvious that an opening is provided between them which extends through from side to side of the box, being open on both faces.

When the handle F is arranged in working 95 position by fastening the link E to the standard by means of the pin G, its inner end is intended to enter the box H in the piston-rod loosely. This end of the handle is provided with small rollers *f*, which fit in the box, being arranged on each side of the handle, preferably as shown in the drawings, and adapted

to about fill the box. It is obvious that as the handle works upon a fixed pivot and the piston moves in a straight line there must be provision made at the joint between the piston-rod and the handle for the changing position of the inner end of the handle as it moves through its arc of motion. This provision is found in the loose joint-connection just described; for, obviously, as the handle is vibrated and the piston-rod moved up and down the inner end of the handle will move freely back and forth within the box, the rollers facilitating this action by overcoming the friction, and there will be no binding in the working of the pump by means of the handle. A hole is provided in the upper end of the piston-rod, by means of which it may be attached to the connecting-rod of a windmill whenever it is desired to operate the pump by this power. Any other ordinary device for making this connection may be employed, as the means adopted for this purpose constitutes no part of my present invention.

When the pump is to be worked by a windmill or any other power, it is of course desirable to disconnect the handle from the piston-rod, so as to avoid the useless vibration of the handle. This is readily effected in my invention by simply removing the pin G, when, obviously, the handle may be pulled outward until it is disconnected from the piston-rod, the link E swinging outward within its loop to permit this action, and finally resting upon the cross-bar at the outer portion of the loop. When it is desired to work the pump by the handle again, it is only necessary to throw the link up and insert the inner end of the handle in the box of the piston-rod and fasten the link to the standard by again inserting the pin G.

It will be seen from this description that the connection between the handle and the piston-rod is an entirely loose one, requiring no separate piece to fasten the two together. Connection and disconnection between the two parts is effected simply by swinging the link on which the handle is mounted, and the latter is fastened in place for working the pump by the handle by inserting the pin G in the proper holes, and unfastened to permit the handle to be pulled away from the piston-rod by simply removing the same pin. When the pump is to be operated by the handle, it will be seen that the pivot of the latter is fixed, for the link on which it is mounted is then made fast, so that it cannot swing.

I do not wish to be understood as limiting

myself to the precise details of construction herein shown and described. The handle may be differently mounted and differently connected to the piston-rod and yet the main features of my improvement retained, which are the support of the handle upon the standard by means which provide a fixed pivot for the handle in working position, and at the same time permit the latter to be pulled outward to disconnect it from the piston-rod, and a loose joint or connection between the handle and the piston-rod, whereby these two parts may be connected and disconnected without the interposition of any additional device, and the handle is permitted to move transversely to the rod. Other parts of the structure may also be changed in details without departing from the main features of my improvement.

Having thus described my invention, what I claim as new, and desire to secure by Letters Patent, is—

1. The pump-handle, in combination with a pivotal support therefor, adjustable at its swinging end, and a fastening device whereby said support may be secured in a fixed and rigid working position, substantially as and for the purposes specified.

2. The piston-rod provided with a device for receiving the end of the handle, in combination with the pump-handle applied to the rod, but not attached thereto, an adjustable pivotal support for said handle, and a fastening device whereby said support may be secured in a fixed working position, substantially as specified.

3. The pump piston-rod C, provided with box H, in combination with the handle F, adjustable in the direction of its length, provided at its inner end with rollers f, arranged to enter and fit the box H, and the adjustable pivoted link E, substantially as specified.

4. The pump-handle F, in combination with the pivoted link E, the standard D, and the fastening-pin G, substantially as specified.

5. The standard D, provided with the side loop, d' d'', in combination with the pump-handle F, pivoted link E, and fastening pin G, substantially as specified.

6. The pump piston-rod C, provided with the box H, in combination with the standard D, pump-handle F, pivoted link E, and fastening device G, substantially as specified.

JOHN Q. ADAMS.
